DETERGENT PASTE

Jonas Kamlet, New York, N. Y., assignor to Boyle-Midway Inc., New York, N. Y., a corporation of Delaware

No Drawing. Application July 14, 1945,
Serial No. 605,186

7 Claims. (Cl. 252—110)

1

This invention relates to a detergent paste containing trisodium phosphate, and more particularly to a detergent paste suitable for household, toilet, laundry and industrial use which contains finely divided, uniformly distributed, solid trisodium phosphate in non-abrasive form. It has for one object to provide a composition in paste form possessing as nearly as possible the characteristics of an ideal all-purpose detergent. It has for a further object to provide a process for the manufacture of an inexpensive detergent paste composition possessing various desirable properties. Other objects and advantages will be apparent from the following description.

An ideal all-purpose detergent should possess the following characteristics:

- (a) A limited high pH value in dilute solution coupled with absence of causticity;
- (b) Good buffering properties;
- (c) Good emulsifying activity;
- (d) Marked surface-tension-lowering activity;
- (e) Lack of abrasive properties;
- (f) Ability to form copious suds;
- (g) Absence of insoluble-soap or scum formation on solution in hard water; and
- (h) Absence of irritating dust due to the presence of "fines."

Trisodium phosphate (Na_3PO_4) has long been used as a detergent and as an ingredient of detergent mixtures (e. g., as a "builder" for laundry soap, as a component of soap powders, etc.). It possesses the first three characteristics enumerated above to a satisfactory extent.

(a) Trisodium phosphate gives solutions of higher pH value than any other common non-caustic alkali (i. e., with the exception of such excessively caustic alkalis as sodium hydroxide). A 0.033% solution of trisodium phosphate has a pH of 10.80 (sodium hydroxide—pH 11.85; sodium carbonate—pH 10.65); a 0.66% solution of trisodium phosphate has a pH of 11.45 (sodium hydroxide—pH 12.90; sodium carbonate—pH 11.20).

(b) Trisodium phosphate possesses excellent buffering properties. Thus, it retains its detergency in the presence of acid soils which would destroy the cleansing ability of other alkalis.

(c) Trisodium phosphate has remarkable properties as an emulsifying agent for saponifiable oils and greases, approaching in emulsifying power the properties of a colloidal dispersing and emulsifying agent. No completely satisfactory explanation of this property has yet been put forth. It is probable, however, that this emulsifying activity is due to the ability of trisodium

phosphate to form sodium soaps by double displacement reactions with greases (which are heavy metal salts of fatty acids) and by saponification of fats and oils. These sodium soaps, formed at the interface of the soil particle, and the aqueous solution are powerful emulsifying agents, particularly in the nascent or formative stage.

However, crystalline trisodium phosphate does not possess other characteristics of an ideal all-purpose detergent: It does not possess any marked surface tension-lowering activity; the solid compound, either anhydrous or as the hydrate, forms harsh and abrasive crystals; it is totally devoid of sudsing properties; it forms a scum of insoluble calcium- and magnesium phosphates in hard water and it usually contains a considerable amount of "fines" which cause an irritating and sternutatory dust when the dry powder is shaken.

By this invention I provide detergents based on trisodium phosphate possessing in addition to the three valuable properties of this compound described above, the other five characteristics attributable to an ideal all-purpose detergent. I provide detergents, based on trisodium phosphate, possessing marked surface-tension-lowering activity, lack of abrasive properties, good sudsing qualities, absence of scum or insoluble-compound formation in hard water and absence of irritating dust or "fines."

I have discovered that when hot emulsions of:

- (a) Trisodium phosphate,
- (b) A surface-active compound capable of sequestering or forming soluble compounds with alkali-earth metal ions, in amount from 0.5% to 5.0% of the total weight of the composition,
- (c) An emulsifying agent chosen from the group of compounds consisting of the salts of aliphatic acids containing from 7 to 22 carbon atoms with the alkali metals and the primary, secondary and tertiary hydroxyalkylamines in amount from 1.0% to 5.0% of the total weight of the composition, and
- (d) Water, in amount between two and three times the weight of the trisodium phosphate, taken as anhydrous Na_3PO_4 ,

are cooled (or permitted to cool), a stable and uniform detergent paste is obtained. I have further discovered that under these conditions, although insufficient water is present to dissolve all the trisodium phosphate at room temperature,

the latter is present in a form completely devoid of harmful abrasive properties. These new products possess to a marked degree all of the desirable characteristics of an ideal all-purpose detergent.

The trisodium phosphate, present to the extent of from 22.5% to 32.8% of the total weight of the composition (taken as anhydrous Na_3PO_4) may be used in the form of the anhydrous salt, the monohydrate and/or the dodecahydrate in the formulation of this product.

The surface-active compound capable of sequestering or forming soluble compounds with alkali-earth metal ions may advantageously but not necessarily be chosen from the well-known industrial wetting, penetrating, emulsifying and dispersing agents possessing this property. Typical examples of such agents suitable for the formulation of the detergent products of the present invention are:

Aerosol OT (sodium di-octyl sulfosuccinate)
 Aerosol MA (sodium di-hexyl sulfosuccinate)
 Aerosol AY (sodium di-amyl sulfosuccinate)
 Aerosol OS (sodium isopropyl naphthalene sulfonate)
 Naccanol NR (sodium kerylbenzene sulfonate)
 Sodium lauryl sulfate
 Sodium salts of sulfonated petroleum hydrocarbons
 Gardinol LS (sodium salt of oleyl sulfuric acid)

These may be added to the composition as dry powders, pastes or aqueous solutions, and are present to the extent of from 0.5% to 5.0% (dry basis) of the total weight of the composition.

The emulsifying agent is chosen from the group of compounds consisting of the salts of aliphatic acids containing from 7 to 22 carbon with the alkali metals and the primary, secondary and tertiary hydroxyalkylamines. The aliphatic acids falling within this classification include, for example monobasic acids, such as oenanthic, caprylic, capric, lauric, myristic, palmitic, oleic, stearic, linoleic, arachidic and behenic, and also dibasic acids, such as pimelic, suberic, azelaic, sebacie and brassicic; or they may be mixtures of fatty acids, such as coconut oil fatty acids, palm oil fatty acids, tallow fatty acids, etc.

The emulsifying agents are prepared by combining the above identified acids with an alkali metal hydroxide, such as sodium hydroxide or potassium hydroxide, or with a primary, secondary or tertiary hydroxyalkylamine. The following are examples of such typical hydroxyalkylamines: Primary—ethanolamine, propanolamine, 2-amino, 2-methylpropandiol-1,3, hydroxyethylethylene diamine secondary—diethanolamine, dipropanolamine, N-methylethanolamine, N-butyethanolamine; tertiary—triethanolamine, triisopropanolamine, N,N-dimethylethanolamine, N-methyl, N-ethylethanolamine.

This salt formation may be effected by combining the acids and the bases in stoichiometric amounts in aqueous solution. In the case of the organic bases, melting these together with equimolar equivalents of the acids suffices to form the corresponding salt by addition. The salt formation may be effected extraneously, and the resultant compound added to the composition as an emulsifying agent. Alternatively, the base and the acid may be combined in the course of formulation and the resultant salt formed in situ where it acts as an emulsifying agent.

The concentration of the emulsifying agent, anhydrous basis, is from 1.0% to 5.0% of the total

weight of the composition. This suffices to yield a stable and uniform emulsion.

The water is present to the extent of from 60.0% to 73.9% of the total weight of the composition and from two to three times the weight of the trisodium phosphate, taken as anhydrous Na_3PO_4 . Within the above delineated limits of concentration for each component, a detergent paste of the desired characteristics is obtained.

The emulsion is formulated by dissolving the trisodium phosphate in the water heated to between 75° C. and 100° C. If the monohydrate, octahydrate, or the dodecahydrate of trisodium phosphate is employed, the water content of the crystalline material must be reckoned as part of the water content of the final product. Trisodium phosphate dodecahydrate will dissolve in its water of crystallization when heated above 75° C., and the resultant solution may be diluted with hot water to obtain the desired $Na_3PO_4:H_2O$ ratio.

To this hot solution are now added with vigorous agitation the surface-active agent and the emulsifying agent, each or both of these being in solid, paste or liquid form. Stirring is continued while the emulsion cools, or is cooled by extraneous means. When the emulsion commences to thicken (e. g., around 50° to 60° C.), it is poured into containers and permitted to gel to a homogeneous paste.

An alternative method is to dissolve the trisodium phosphate, the surface active agent and the basic component of the emulsifying agent in the water, heated to between 75° C. and 100° C. To this well stirred, hot solution the acidic component of the emulsifying agent is now added. The emulsifying agent is formed in situ and immediately dispersed in the solution. The emulsion is cooled to the thickening point, as above, and poured into containers where it is permitted to gel.

Another alternative method is to dissolve the trisodium phosphate and the surface active agent in the hot water, disperse the fatty acid in the hot solution (taking advantage of the excellent fat-emulsifying properties of the trisodium phosphate) and add the basic component of the emulsifying agent thereto. Here again, the formation of the emulsifying agent occurs in situ, and the emulsion is treated as above.

Ordinarily when a concentrated hot aqueous solution of trisodium phosphate is cooled, or permitted to cool, the trisodium phosphate will precipitate as hydrated crystals. For some purposes these crystals are satisfactory, but for an ideal all-purpose detergent they have the disadvantage of being harshly abrasive, a property that obviously unfit them for many purposes for which a detergent is used. By following the process comprised in my invention and observing the limitations as to quantities and conditions disclosed, I have discovered that trisodium phosphate can be incorporated in relatively high concentration into a detergent paste in such a way as to keep available its above-described desirable properties but to eliminate entirely its usual harsh abrasive properties. While I do not wish to be limited to any particular theory or mechanism in explaining this result, it appears that the conditions of cooling the concentrated aqueous solution of trisodium phosphate in the presence of a surface-active agent and an emulsifying agent as above described result in the precipitation of the trisodium phosphate in an extremely finely divided and thoroughly dis-

persed form. The salt so precipitated appears to be amorphous but may be microcrystalline, and its particles are probably individually surrounded by an adsorbed film of the colloids present. Whatever the explanation, I obtain a detergent paste containing a relatively high concentration of trisodium phosphate, a surface-active material, an emulsifying agent and insufficient water to dissolve the trisodium phosphate at room temperature, in which the trisodium phosphate retains its desirable detergent and chemical properties but is devoid of undesirable abrasive properties.

The addition of an emulsifying agent chosen from the group delineated above aids in obtaining a uniform emulsion when hot which on cooling gels to a uniform paste containing solid, dispersed trisodium phosphate in the desired form; it furthermore enhances and accentuates the emulsifying action of the trisodium phosphate on greases, fats and oily soils.

The detergent pastes of the present invention, containing from 22.5% to 32.8% of trisodium phosphate on an anhydrous basis (Na_3PO_4), have an actual or equivalent content of from 52.1% to 76.0% of the dodecahydrate ($\text{Na}_3\text{PO}_4 \cdot 12\text{H}_2\text{O}$). Since the dodecahydrate is by far the most common commercial form of trisodium phosphate, these pastes possess to a marked degree the excellent emulsifying activity, good buffering properties and high pH in dilute solution obtained by the use of powdered detergents based on commercial trisodium phosphate.

In addition, they possess the other characteristics desirable in an all-purpose detergent and not present in trisodium phosphate-containing detergent powders and particularly are free of the abrasive properties of the latter.

The presence of the calcium-ion-sequestering surface-active agent in concentrations between 0.5% and 5.0% in the formulation serves to reduce the surface tension sufficiently to effect excellent wetting of the material being cleansed by the detergent solution. It also lowers the interfacial tension between the particles of soil and the detergent solution and thus facilitates the cleaning process. Not all surface-active agents possess surface-tension-lowering properties. Certain non-ionic dispersing agents owe their activity to their ability to decrease the mutual attraction between suspended or dispersed particles, thereby lowering the viscosity of the dispersions and effecting a stabilization. However, calcium-ion-sequestering surface-active agents are anionic in nature and possess marked surface-tension-lowering properties. This group of anionic surface active agents includes the sulfonated oils (such as Turkey red oil), the sulfonated higher alkanols and higher alkyl sulfates, the sulfonated naphthenates, the sulfonated petroleum fractions, the aromatic sulfonates (such as the sulfonated alkylnaphthalenes, the sulfonated alkyl benzenes and the Twitchell reagents), the esters of sulfosuccinic acids, the sulfonated amides, etc.

I am aware that it has been proposed by Frost (U. S. Patent 1,885,905, patented November 1, 1932) to co-crystallize trisodium phosphate with less than 1%, and preferably about 0.3% of a fatty acid soap. The resultant crystals are stated to have a satin-like sheen or luster and to be less susceptible to caking or lumping under varying humidity conditions. Frost's product, however, is not only entirely different in chemical composition and physical form from the products of this invention, but the properties of the trisodium

phosphate crystals in his product are the very properties that this invention aims to and does eliminate. In Frost's product, crystallization is not in any way interfered with; in fact Frost states that larger and better formed crystals of trisodium phosphate will develop in his product than in the ordinary commercial salt. The product of my invention, on the other hand, is a non-crystalline paste, and (as pointed out above) the trisodium phosphate is uniformly distributed in the paste in amorphous form or, if crystalline, in such a microcrystalline state as to behave for practical detergent purposes as non-crystalline and be free of harsh abrasive properties.

The products of the present invention will form copious suds in water, cold as well as warm. This property is primarily due to the content of surface active agents in the formulation, since both detergency and foaming are phenomena closely related to the lowering of surface tension. The sudsing of the product is also enhanced materially by the presence of the emulsifying agent. Salts of oleic acid, coconut oil fatty acids, hydrogenated coconut oil fatty acids, palm oil fatty acids, castor oil fatty acids, olive oil fatty acids, myristic acid and linoleic acid are among the best producers of foam or suds.

The presence of the calcium-ion-sequestering surface active agent also inhibits scum formation due to precipitation of insoluble calcium and magnesium phosphates. This serves to prevent undesirable contamination of fabrics, hair, glassware, etc., during washing and subsequent rinsing operations, to prevent the formation of a ring of dirt around wash basins, bath tubs, etc., and to prevent the spotting of clothes, or uneven application of dyes in dyeing operations. It also serves to prevent the precipitation of scale in steam boilers through and in which solutions of the detergent compositions of the present invention may be circulated or stored.

Finally, it may be noted that the detergent compositions of the present invention are totally devoid of irritating or sternutatory dusts or "fines" since they are produced in the form of gels or pastes.

It is obvious that coloring agents, perfuming agents, deodorizing agents, and other ancillary substances may be incorporated in the products of the present invention without changing the basic nature thereof.

The detergent pastes described in the present application may be used for washing dishes, glassware, china, greasy and charred cooking utensils, silverware, linoleum and composition floors, sinks, toilet bowls, refrigerators, tables, tile, marble, terrazzo, painted and unpainted walls, furniture, for all laundering purposes, for badly grimed overalls, as a detergent paste for mechanics' hands, for softening hard water in industrial plants, laundry and bath, for mopping, scrubbing, metal cleaning, for drapes, rugs, blankets, woolens, etc., etc., or wherever an all-purpose detergent is applicable.

The following examples are given to define and to illustrate the present invention, but in no way to limit it as to reagents, proportions or conditions described therein. Obvious modifications will occur to any person skilled in the art. All proportions given are parts by weight.

Example I

300.0 parts of anhydrous trisodium phosphate,
20.0 parts of Naccanol NR (sodium kerylbenzene

sulfonate, manufactured by the National Aniline Division, Allied Chemical & Dye Corporation) and 2.0 parts of potassium hydroxide are dissolved in 662.0 parts of water heated to between 75° C. and 100° C. To the resultant solution there are added, with vigorous stirring, 11.0 parts of oleic acid and 5.0 parts of pine oil. Agitation is continued while the emulsion is cooled. When the temperature has fallen to between 50° C. and 60° C., the emulsion is poured into its ultimate containers (e. g., bottles, jars, tins, etc.) where it is permitted to set to a paste. The gelling process may be accelerated by cooling or chilling the filled container.

Example II

521.6 parts of trisodium phosphate dodecahydrate are heated at 75° C. to 85° C. until it has dissolved in its water of crystallization. 200.0 parts of a 25% aqueous solution of Aerosol OT (sodium di-octyl sulfosuccinate), 50.0 parts of the monoethanolamine salt of coconut oil fatty acids, 0.4 part of the sodium salt of fluorescein (uranine WSS) and 228.0 parts of boiling water are added with vigorous agitation. The resultant emulsion is stirred until it has cooled to within the 50° C.-to-60° C. range, and is then poured into its ultimate containers and permitted to gel.

The emulsifying agent is prepared by melting together coconut oil fatty acids with 30.0% of their weight of monoethanolamine.

Example III

305.0 parts of anhydrous trisodium phosphate and 25.0 parts of sodium isopropyl naphthalene sulfonate are dissolved in 635.0 parts of water heated to between 75° C. and 100° C., and 12.5 parts of palm oil fatty acids are dispersed in the resultant solution. To the well agitated reaction mixtures are now added 7.5 parts of triethanolamine and 15.0 parts of limonene. The emulsion thus obtained is cooled to incipient gelling and poured into its ultimate containers.

Example IV

695.4 parts of trisodium phosphate dodecahydrate are dissolved in 204.6 parts of boiling water, and 50.0 parts of sodium lauryl sulfate and 50.0 parts of sodium myristate are added to the resultant solution with vigorous stirring. When a uniform emulsion is obtained, it is cooled to between 55° C. and 60° C., and poured into its ultimate containers where it is permitted to gel.

Example V

240.0 parts of trisodium phosphate anhydrous, 8.0 parts of Naccanol FSNO (a purified grade of sodium kerylbenzene sulfonate) and 6.3 parts of diethanolamine are dissolved in 720.0 parts of boiling water. 15.7 parts of olive oil fatty acids and 10.0 parts of terpineol are now added to the vigorously agitated solution. The resultant emulsion is allowed to cool to 50° C.-55° C. and is then poured into containers and permitted to gel.

I claim:

1. A detergent paste comprising from about 22% to about 33% trisodium phosphate calculated as the anhydrous salt, the trisodium phosphate being in a solid, finely divided, uniformly dispersed form, devoid of harsh abrasive properties, a surface-active material capable of solubilizing alkali-earth metal compounds under detergent conditions and chosen from the group of compounds consisting of sulfonated and sulfated non-soap detergents, an emulsifying agent chosen from the group of compounds consisting

of the salts of aliphatic acids containing from 7 to 22 carbon atoms with the alkali metals and the primary, secondary and tertiary hydroxyl-alkylamines in an amount sufficient to maintain the ingredients of the mixture in dispersed state, and water in an amount insufficient to dissolve all the trisodium phosphate in the mixture at room temperature but sufficient to impart to the mixture a pasty consistency.

2. A detergent paste containing from about 22% to about 33% trisodium phosphate calculated as the anhydrous salt, from about 0.5% to about 5.0% of a surface-active compound capable of solubilizing alkali-earth-metal compounds under detergent conditions and chosen from the group of compounds consisting of sulfonated and sulfated non-soap detergents, from about 1.0% to about 5.0% of an emulsifying agent chosen from the group of compounds consisting of the

20 salts of aliphatic acids containing from 7 to 22 carbon atoms with the alkali metals and the primary, secondary and tertiary hydroxyl-alkylamines, and from about 60% to about 75% of water, the amount of water being between two and three times the amount of the trisodium phosphate.

3. A detergent paste as defined in claim 2, in which the emulsifying agent is potassium oleate.

4. A detergent paste as defined in claim 2, in which the emulsifying agent is a hydroxyalkylamine salt of an aliphatic acid containing from 7 to 22 carbon atoms.

5. A detergent paste as defined in claim 2, in which the surface-active compound is sodium kerylbenzene sulfonate.

6. A process for the manufacture of a detergent paste, which comprises mixing trisodium phosphate, a surface-active material capable of solubilizing alkali-earth metal compounds under detergent conditions and chosen from the group of compounds consisting of sulfonated and sulfated non-soap detergents, an emulsifying agent chosen from the group of compounds consisting of the salts of aliphatic acids containing from 7

45 to 22 carbon atoms with the alkali metals and the primary, secondary and tertiary hydroxyl-alkylamines in an amount sufficient to maintain the ingredients of the mixture in dispersed state, and water in an amount insufficient to dissolve all the trisodium phosphate in the mixture at room temperature but sufficient to impart to the mixture a pasty consistency at room temperature, heating the mixture to a temperature between 75° and 100° C., violently agitating the mixture while heated to effect uniform dispersion of the ingredients, and cooling the resultant emulsion to a temperature below 75° C.

7. A process for the manufacture of a detergent paste, which combines mixing from about 22% to about 33% trisodium phosphate calculated as the anhydrous salt, from about 0.5% to about 5.0% of a surface-active compound capable of solubilizing alkali-earth metal compounds under detergent conditions and chosen from the group of compounds consisting of sulfonated and sulfated non-soap detergents, from about 1.0% to about 5.0% of an emulsifying agent chosen from the group of compounds consisting of the salts of aliphatic acids containing from 7

65 to 22 carbon atoms with the alkali metals and the primary, secondary and tertiary hydroxyl-alkylamines and from about 60% to about 75% of water, the amount of water being between two and three times the amount of trisodium phosphate, heating the mixture to a temperature be-

tween 75° and 100° C., violently agitating the mixture while heated to effect uniform dispersion of the ingredients, and cooling the resultant emulsion to a temperature below 75° C.
